UNITED STATES PATENT OFFICE.

VICTOR ARDITO, OF HOBOKEN, NEW JERSEY.

CUSPIDOR.

No. 853,617.

Specification of Letters Patent.

Patented May 14, 1907.

Application filed July 16, 1906. Serial No. 326,417.

To all whom it may concern:

Be it known that I, VICTOR ARDITO, a citizen of the United States, residing at Hoboken, in the county of Hudson and State of New Jersey, have invented certain new and useful Improvements in Cuspidors, of which the following is a specification.

This invention relates to improvements in cuspidors, and has particular reference to that class of cuspidors in which running water, obtained from the house water supply by being connected therewith, is used for the purpose of cleaning and keeping the same clean and pure, and has for its objects the provision of means for automatically regulating the flow of water into and from said cuspidor, and the provision of suitable means whereby said cuspidor may at all times be cleaned when necessity so demands.

To these ends the invention consists in the novel construction, arrangement, and combination of the several parts of the device as hereinafter described, illustrated in the drawing, and more particularly pointed out in the claim hereunto appended.

In the drawing: Figure 1 is a vertical sectional view of the device, illustrating the construction thereof, and, showing means whereby the same is connected with the house water supply system, means for regulating the amount of water in said device, and means for drawing off the water from said cuspidor to cleanse the same. Figs. 2, and 3 are enlarged details of the valves used in my device, showing their positions relative to the body or casing of the cuspidor.

Referring to the drawing, the numeral 1 indicates the body or casing of the cuspidor, and 2 legs or suitable supports on which it is mounted.

The numeral 3 indicates the funnel-plate adapted to sit and rest upon the top of the body or casing 1, as is usual, and 4 indicates a perforated pipe or ring adapted to sit over and upon said funnel-plate the perforations in said pipe or ring being so positioned that the water flowing therethrough will fall upon the funnel-plate and flow thereover into the opening 5 in the bottom thereof, thus keeping said funnel-plate fresh and clean at all times. Interposed between this perforated ring or pipe 4 and the house supply pipe is a pipe 6 to which said perforated ring or pipe 4 is connected by a hinged cut-off valve 7, the opposite end of said pipe 6 being suitably connected with the house supply pipe. This

pipe 6 is supplied with an emergency or regulating valve 8, located preferably in that portion of the pipe covered by the bottom or casing of cuspidor, as shown, and is primarily for the purpose of regulating the amount of flow through said pipe, and also for the purpose of cutting off the flow when it is desired to remove or repair the cuspidor. Between the valves 7 and 8 at a convenient point in said pipe 6 is a suitable valve 9 adapted to be automatically operated to control the supply of water passing to the perforated ring or pipe 4.

The numeral 10 indicates a suitable float mounted on a suitable hinged rod 11 and connected with the valve 9 and is for the purpose of operating said valve 9 to limit or entirely cut-off the flow of water through said pipe 6 to the perforated ring or pipe 4, as is evident.

The numeral 12 indicates a suitable drain pipe located in the bottom of said cuspidor for the purpose of carrying off the water therefrom to the sewer pipe, and has its upper end curved, as shown at 13, to prevent the passage thereinto of any solid that may be floating on top of the water.

The numeral 14 indicates a suitable wire basket mounted in said cuspidor beneath the funnel-plate 3, and is for the purpose of catching and retaining solids, such as matches, cigars, etc., to prevent them falling to the bottom of the cuspidor, and eventually being carried off through the drain pipe, thus greatly reducing the liability of said drain pipe becoming choked or stopped up. It frequently happens, however, in this class of cuspidors that the drain pipe becomes choked, and as a consequence the water flowing into the cuspidor would soon overflow said cuspidor and pass, with all its filth, onto the floor, and this certainty of overflow, in the event of the clogging of said drain pipe, is the chief, and as far as I know the only objection to this class of cuspidors. To overcome this objection I have provided the automatically operated valve 9 and float 10 which will effectually cut off the flow of water long before it is possible for the water to reach the top of said cuspidor, and thereby absolutely preventing the overflowing of said cuspidor.

The basket 14 may be removed from the body of the device whenever it is desired and emptied, and as the bottom of said basket is above the water in said cuspidor, the solids

held therein will not become soaked or sodden and emit disagreeable odors, such as is so common with the ordinary cuspidor.

The operation of this device is apparent and a further description thereof is thought to be unnecessary.

Having thus fully described my invention what I claim and desire to secure by Letters Patent, is:—

10 A cuspidor of the character described comprising a body or casing having a recess in the upper edge thereof, a funnel plate mounted on the top of said casing and provided with a recess in its periphery, said recess 15 adapted to register with the recess in the

upper edge of said casing, a water supply pipe, an annular perforated distributing ring mounted over said funnel plate, and a pivotal cut-off valve connecting said ring and pipe, said connection sitting and resting in 20 the recesses in said funnel plate and casing when in normal position, and a suitable drain pipe in the bottom of said casing.

In testimony whereof I have signed my name to this specification in the presence of 25 two subscribing witnesses.

VICTOR ARDITO.
